DESIGN FOR A BRASSIERE

Pierre Amyot, Quebec, Quebec, Canada

Application March 6, 1943, Serial No. 109,688

Term of patent 7 years

To all whom it may concern:

Be it known that I, Pierre Amyot, a subject of the King of Great Britain and resident of the city of Quebec, in the Province of Quebec, and Dominion of Canada, have invented a new, original, and ornamental Design for a Brassiere, of which the following is a specification, reference being had to the accompanying drawing, forming a part thereof.

In the accompanying drawing:

I claim:

The ornamental design for a brassiere, as shown.

PIERRE AMYOT.
